UNITED STATES PATENT OFFICE.

CASPAR DRUEDING, OF PHILADELPHIA, PENNSYLVANIA, ASSIGNOR TO DRUEDING BROTHERS COMPANY, OF PHILADELPHIA, PENNSYLVANIA.

SKIN-STRETCHING BOARD.

1,118,641.

Specification of Letters Patent. Patented Nov. 24, 1914.

Application filed March 5, 1914. Serial No. 822,736.

To all whom it may concern:

Be it known that I, CASPAR DRUEDING, a citizen of the United States, residing at Philadelphia, in the county of Philadelphia and State of Pennsylvania, have invented 5 certain new and useful Improvements in Skin-Stretching Boards, of which the following is a specification.

My invention relates to improvements in 10 skin stretching boards, the object of the invention being to provide a board to which the skin may be secured, and which comprises a plurality of parts all of which are movable relative to each other, so that the 15 skin can be uniformly stretched in all directions.

A further object is to provide a board of 20 the character stated having means for compelling each one of the sections of the board 20 to be moved away from a normal position, and permit the sections to be moved independently so as to allow the neck portion of the skin to be stretched after the body portion has been stretched or vice versa.

25 A further object is to provide a board of the character stated which will be of extremely inexpensive construction, strong and durable in use.

With these and other objects in view, the 30 invention consists in certain novel features of construction and combinations and arrangements of parts as will be more fully hereinafter described and pointed out in the claims.

35 In the accompanying drawings: Figure 1 is a view in front elevation partly in section illustrating one form of my improved board showing in full lines the board in contracted or normal position, and in dotted 40 lines the sections extended. Fig. 2 is a view in section on the line 2—2 of Fig. 1. Fig. 3 is a fragmentary view in section on an enlarged scale on the line 3—3 of Fig. 1. Fig. 4 is a view in elevation illustrating a 45 modification. Fig. 5 is a fragmentary view in section on an enlarged scale on the line 5—5 of Fig. 4. Fig. 6 is a view in section on the line 6—6 of Fig. 5. Fig. 7 is a view in rear elevation illustrating another modification, and Fig. 8 is a fragmentary sectional perspective view illustrating the mounting of one of the operating rods.

Referring to my improved board illustrated in Figs. 1, 2, and 3, 1 and 2 represent two opposed sections which are of gen-

eral L-shape with their lower shorter members abutting together when the board is in closed position as shown in Fig. 1. 3 represents the end section which has beveled ends 4 adapted to engage the beveled upper 60 ends 5 of the sections 1 and 2, so that when the several sections are together, they form a rectangular board with a rectangular opening 6 in the center thereof, and present a smooth surface against which the 65 skin 8 indicated in dotted lines is secured by nails 9 or other suitable fastening means. The sections 1, 2, and 3, are preferably wood, and they are made up of suitable boards and timbers, so that they present 70 smooth surfaces at opposite sides, the sections being shown hollow, although they may be otherwise formed as desired. On the outer edges of sections 1, and 2, metal blocks 10 are secured by bolts 11 and nuts 75 12. These blocks 10 have screw-threaded 12. These blocks 10 have screw-threaded openings for the reception of rods 7, the latter having threaded ends to engage the threaded openings in the blocks, and it is to be understood that these ends of the 80 rods 7 have right and left hand screw-threads at their respective ends and are provided at one end with hand holds 13 to facilitate their turning movement. One of the rods 7 extends through openings 14 in 85 metal blocks 15, and rods 16 have swiveled connection at their inner ends with the blocks 15 as shown at 17 in Fig. 3. These rods 16 are positioned at right angles to the rods 7, and extend through the end section 3 and have screw-threaded portions engaging screw-threaded openings in blocks 10 secured by bolts 11 and nuts 12 to the 90 edge of end section 3. In other words, the blocks 10 of the end sections are precisely 95 like the blocks for the side sections, and hence they are given similar reference characters and will be given the same reference characters in all of the different modifications hereinafter referred to. In operation, 100 the skin 8 is secured by nails 9 to the sections 1, 2, and 3, the neck portion of the skin being preferably secured to the end section 3. By manipulating the several rods 7 and 16, all of the sections can be moved 105 relative to each other to stretch the skin. The preferable operation is to first separate sections 1 and 2, causing the body portion of the skin to stretch laterally or transversely, and then move the end section 3 to 110

stretch the neck portion of the skin and stretch the skin longitudinally. The invention, of course, is not limited to the particular manner of operation, as this will 5 depend upon the judgment of the user, and the character of the skins stretched.

In the modification illustrated in Figs. 4, 5, and 6, I provide four sections 18, 19, 20, and 21, all having inclined ends 22 so that 10 they can snugly fit together and comprise a rectangular board when the sections are in closed position. One of the sections 21 is preferably wider than the others, so that its inner edge 23 extends inwardly beyond the 15 inner edges of the other sections, which is a desirable construction to receive the neck portion of the skin or to allow the connection of a smaller skin than would be possible without this extension. The sections 18, 19, 20, and 21, are all moved by means of rods 24, a pair of such rods being extended 25 through opposed sections and having right and left hand screw-threads at their respective ends engaging in blocks 10 as in the preferred form. The rods 24, where they cross, are coupled by metal blocks 25 having openings 26 therethrough at right angles to each other through which the rods project. This 30 detail of construction is clearly shown in Figs. 5 and 6. As the parts are normally operated in a horizontal position, the coupling blocks 25 are all that is necessary to hold the sections and permit all of the sections to be moved toward and away from 35 their inner position as is desired in stretching the skin.

In the modification illustrated in Fig. 7, I have shown but two sections 27, and 28, which are movable toward and away from 40 each other by rods 29 having right and left hand screw-threads at their respective ends projected through blocks 10 as in the other forms. By manipulating the rods, after the skin is secured to the sections, the sections 45 may be moved away from each other to stretch the skin.

In all of the forms, it will be observed that I provide on the side sections at their upper ends, hangers 30 which permit the 50 support of a number of such boards upon parallel bars (not shown), and at the lower portion of the sections, I provide casters 31 which permit the board to be readily moved about the floor from one place to another.

With all forms of my improved board, it 55 will be noted that all sections to which the skin is secured are movable, so that every portion of the skin is stretched alike, and while I have illustrated my improvements 60 in connection with boards having two, three, or four sections, I would have it understood

that my invention is not limited to the particular number of sections, as I may employ other number of sections, but in any and all events will move all of the sections so 65 that all portions of the skin will be stretched.

Various slight changes might be made in the general form and arrangement of parts described without departing from my invention, and hence I do not limit myself to the 70 precise details set forth, but consider myself at liberty to make such changes and alterations as fairly fall within the spirit and scope of the appended claims.

Having thus described my invention, what 75 I claim as new and desire to secure by Letters Patent is:

1. A skin stretching board comprising a plurality of sections, blocks secured to the edges of the sections and having threaded 80 openings therein, rods projected through the blocks and having threads engaging the threaded openings in the blocks, hand holds on the rods adapted to permit the turning of the rods, whereby the sections may be 85 adjusted toward and away from each other, and blocks coupling the rods at right angles to each other, substantially as described.

2. A skin stretching board of the character stated comprising three sections, two of 90 said sections of general L-shape having their longer ends inclined, an end section located between the inclined ends of the first-mentioned section and having inclined ends whereby when said sections are together, a 95 rectangular opening is formed between them, and means for moving all of the sections, substantially as described.

3. A skin stretching board of the character stated comprising three sections, two of 100 said sections of general L-shape having their longer ends inclined, an end section located between the inclined ends of the first-mentioned section and having inclined ends 105 whereby when said sections are together, a rectangular opening is formed between them, parallel rods projected through the first-mentioned sections and having screw-threaded engagement therewith, other rods projected through the last-mentioned section and having screw-threaded engagement therewith, devices coupling the last-mentioned rods with one of the first-mentioned rods, and means on each of the rods for turning the same, substantially as described. 110

In testimony whereof I have signed my name to this specification in the presence of two subscribing witnesses.

CASPAR DRUEDING.
